United States Patent

Des. 241,065
Patented Aug. 17, 1976

241,065

PENDANT OR SIMILAR ARTICLE

Margarett C. Roberts, Providence, R.I., assignor to Reed and Barton Corporation, Taunton, Mass.

Filed May 28, 1974, Ser. No. 473,517

Term of patent 3½ years

Int. Cl. D11—01

U.S. Cl. D45—16 B

FIG. 1

FIG. 2

FIG. 1 is a front elevational view of a pendant or similar article showing my new design; and

FIG. 2 is a side elevational view thereof, from the right. The left side is a mirror image of the right, and the back is plain and unornamented.

I claim:

The ornamental design for a pendant or similar article, substantially as shown and described.
